**DISPOSABLE MOUNTING MEMBER FOR ADJUST-
ABLY POSITIONING A DENTAL FACE BOW**

Robert L. Lee, Colton, and Jacob L. Schwartz, Covina, Calif., assignors to DentoNomics Corporation, Inglewood, Calif., a corporation of California

Continuation of design applications Ser. No. 12,339 and 12,340, both June 13, 1968. This application Nov. 4, 1968, Ser. No. 14,292

Term of patent 14 years

Int. Cl. D24—03

U.S. Cl. D24—1

FIG. 1.

FIG. 2.

FIG. 3.

FIG. 4.

FIG. 5.

FIG. 7.

FIG. 6.

FIG. 9.

FIG. 8.

FIG. 11.

FIG. 10.

FIGURE 1 is a perspective view of a disposable mounting member for adjustably positioning a dental face bow showing my new design;

FIGURE 2 is a front elevation thereof;

FIGURE 3 is a side elevational view taken from the right side of the mounting cup as shown in FIGURE 2;

FIGURE 4 is a top plan view of the device of FIGURE 1;

FIGURE 5 is a bottom plan view of the device of FIGURE 1;

FIGURE 6 is a perspective view of a modified embodiment of the disposable mounting member for adjustably positioning a dental face bow illustrated in FIGURE 1;

FIGURE 7 is a front elevational thereof;

FIGURE 8 is a side elevation thereof, the opposite side being a mirror image of the side shown;

FIGURE 9 is a top plan view thereof;

FIGURE 10 is a bottom plan view thereof; and

FIGURE 11 is a rear elevation thereof.

This is a continuation of design application Ser. Nos. D. 12,339 and D. 12,340 filed June 13, 1968 and now abandoned.

We claim:

The ornamental design for a disposable mounting member for adjustably positioning a dental face bow, as shown and described.
